UNITED STATES PATENT OFFICE

EMIEL P. SEGHERS, OF CHICAGO, ILLINOIS

GREASE GUN

Application filed January 17, 1927. Serial No. 161,473.

This invention relates to a device for injecting lubricating material into bearings and has for one of its objects the provision of a device of the class named which may be easily filled.

A further object is to provide improved means for attaching the gun to the bearing.

Other objects will appear from the following description.

10 The invention is exemplified in the combination and arrangement of parts shown in the accompanying drawing and described in the following specification, and it is more particularly pointed out in the appended claims.

15 In the drawings:—

Fig. 1 is a longitudinal sectional view of a grease gun embodying one form of the present invention;

20 Fig. 2 is a fragmentary elevation of a portion of the grease gun shown in Fig. 1;

Fig. 3 is a section on line 3—3 of Fig. 2;

Fig. 4 is an elevation of a nipple for attaching the gun to a bearing to be lubricated;

25 Fig. 5 is a section on line 5—5 of Fig. 1;

Fig. 6 is a section similar to Fig. 5 but showing a slightly modified form of construction.

This invention is, in part, a continuation of my prior application Serial No. 58,220, filed September 24, 1925.

30 In the drawing, the numeral 10 designates the cylinder or barrel of a grease gun having a piston 11 movable longitudinally of the barrel 10. The piston 11 is provided with a stem 12 threaded in a cap 13 which, in turn, is threaded on the rear end of the barrel 10. The piston 11 is provided with a cup-shaped leather 14 which is held in place by a disc 15 and a nut 16. The nut 16 is preferably attached to the end of the stem 12 by a left hand thread so that when the stem 12 is withdrawn to its extreme position shown in Fig. 1, further rotation of the stem 12 will tend to tighten the nut 16 in place on the piston 11, thus avoiding any danger of detachment of the piston from the stem. With this arrangement, it is possible to use the stem 12 for unscrewing the cap 13 from the end of the barrel 10. The outside threads on the end of the barrel 10 for retaining the cap 13 extend along the barrel 10 a greater distance than is

necessary for engagement with the cap and a ring 17 is threaded on the barrel in front of the cap 13. In the manufacture of the device, the ring 17 may be originally made integral with the flange of the cap 13 and after it has been threaded, a portion of the flange may be severed to form the ring 17. This has been found to effect economy in the manufacture of the device.

35 The ring 17, as shown in Fig. 2, is provided with a peripherally extending notch 18 in its forward end which engages the spring stop 19 secured to the barrel 10. The stop 19 may be sprung outwardly to permit the ring 17 to be threaded into place or to be removed if desired. When the parts are in place, however, the stop 19 limits rotation of the ring 17 to a partial rotation. The ring 17 is formed outwardly at one portion of its circumference to provide a boss 20, leaving a

40 recess 21 between the ring and the surface of the barrel 10. The boss 20 is offset toward one edge of the ring 17 so that the recess 21 is open at one edge thereof but closed at the opposite edge thereof, as shown in Fig. 1. A thumb screw 22 is threaded through the boss 20 and forms a needle valve for closing a perforation 23 through the wall of the barrel 10. When the ring 17 is rotated to one extremity of its movement, as determined by

45 the stop 19, the screw 22 will be locked in registration with the perforation 23 so that the screw may be turned inwardly to close tightly the perforation 23, or may be withdrawn to provide a vent through the perforation, opening to atmosphere at the edge of the ring 17 where the recess 21 extends to the edge of the ring. The perforation 23 may also be closed by partially rotating the ring 17 until the recess is brought out of

50 registration with the perforation 23. In this position, the inner face of the ring 17 will close the perforation 23. For some forms of lubrication, this will constitute a sufficiently tight closure and it will not be necessary to use the screw 22. In other forms, however, in order to secure a sufficiently tight closure, it may be found desirable to use the screw 22 by means of which

55 the perforation 23 can be absolutely closed.

The barrel 10 may also be provided with a perforation or vent 24 adjacent the forward end thereof and a screw or needle valve 25 may be employed for closing this vent.

- 5 The forward end of the gun is provided with a discharge spout 26 which is brazed or otherwise tightly secured to the barrel 10. This spout 26 may be internally threaded for attachment to a flexible hose coupling and is 10 also externally threaded to receive a fixed coupling 27. The fixed coupling 27 is provided with an external flange 28 having a tapered perforation 29 therethrough for engaging the tapered end 30 of a nipple 31 15 which is secured to a bearing member 32 or other device to which lubrication is to be supplied. A sleeve 33 fits within the coupling 27 and the forward end of the sleeve bears upon a perforated washer 34 which 20 rests upon the flange 28. The sleeve 33 is provided with an internal flange 35 which forms a valve seat having a perforation arranged to be closed by a valve 36. The valve 36 is provided with a stem 37 guided by an 25 opening in a washer 38 held in the rear end of the sleeve 33. A perforated washer 39 surrounds the valve stem 37 and a spring 40 is interposed between the washer 39 and the washer 38 and operates to close the valve 36. 30 The valve stem 37 is provided with a perforation 41 to permit passage of lubricating material from the barrel 10 past the valve 36 and through the perforation in the flange 35. A packing washer 42 is interposed between 35 the discharge spout 26 and the rear end of the sleeve 33 to hold the sleeve 33 within the coupling 27 and to prevent escape of lubricating material.

The nipple 31 is provided with a spring- 40 held ball valve 43 which opens inwardly when subjected to pressure. The valve 43 is held by a spring 44 which is retained in the opening in the nipple 31 by a split spring ring 45 which engages the circular recess in 45 the wall of the perforation through the nipple 31. The front end of the coupling 27 is provided with a circular recess 46 having a flange or web 47 extending over a portion of the end thereof. The nipple 31 is 50 flattened at one side, as indicated at 48, so that when the flat side of the nipple is brought into registration with the flange 47, the nipple will enter the opening 46. A groove 49 is formed in the periphery of the 55 nipple 31 and is slightly inclined relative to the axis of the nipple to form a cam face for co-operation with the flange 47. The outer face of the groove 49 adjacent the flat side 48 of the nipple may be rounded off, as 60 indicated at 50, to facilitate entrance of the flange 47 into the groove 49 when the connector 27 is rotated relative to the nipple. It will be apparent that when the connector 27 is placed over the nipple and given a partial 65 rotation, the flange 47 will enter the

groove 49 so that rotation will exert a camming action, drawing the connector and nipple together and tightly pressing the tapered portion 30 of the nipple into the tapered seat 29 of the flange 28. This will 70 form a tight connection between the nipple and the connector so that lubrication under pressure within the connector will force the valve 43 open and pass through the interior of the nipple 31. The nipple 31 is provided 75 with a tapered boss 51 which extends beyond the tapered portion 30 and engages a stud 52 on the end of the valve stem 37 to unseat the valve 36. The boss 51 enters the perforation in the washer 34 which is preferably of less diameter than the maximum diameter of the boss 51 so that when lubrication under 80 pressure engages the rear face of the washer 34, the washer will be forced against the tapered surface of the boss 51 and further 85 pack the joint between the nipple 31 and the connector 27. The connector 27 is provided with a flat portion 53, or other index, to indicate the position of the flange 47 so that the connector may be readily placed in proper 90 position on the nipple to cause the flange 47 and flat portion 48 of the nipple to register with each other. The nipple 31 is provided with a hexagonal flange 54 by means of which it may be tightly screwed into the 95 bearing member 32 and the rear end of the connector 27 is also hexagonal to facilitate connection and disconnection with the discharge spout 26. In place of the flange 47, a pin 55 may be secured to the connector 27 100 for co-operation with the cam slot 49, as indicated in Fig. 6.

In operation, the connector 27 is placed over the nipple 31 and given a slight rotation to cause the flange 47 to enter the cam slot 105 49 which draws the nipple and the connector 27 tightly together and opens the valve 36. The stem 12 may then be rotated to place the lubricating material in the barrel 10 under pressure which will force the lubricating material through the perforation 41, past the valve 36 and into the nipple 31. The lubricating material will be prevented from escaping about the nipple by the tapered portion 30 of the nipple seated in the flange 38 110 and by the washer 34 which bears against the stud 51. The pressure of the lubricating material will force the ball valve 43 open to permit passage of the material thru the nipple 31. So long as the leather 14 is in the 115 rear of the perforation 23, the perforation 23 is kept closed to prevent escape of lubricating material thru the perforation. During passage of lubricating material, the screw valve 25 tightly closes the perforation 120 24.

When it is desired to refill the gun, the piston 11 is retracted until the leather 14 clears the perforation 23, as indicated in Fig. 1. The connector 27 or discharge nozzle 130

is then connected with the container for lubricating material in which the lubricant may be placed under pressure, such as the container shown in my prior application above referred to, or any other suitable device from which the material may be ejected under pressure. The material is then subjected to pressure and forced into the barrel 10 through its discharge spout. The air 5 within the barrel escaping through the vent 23 which is at this time left open for this purpose. As soon as the gun has become filled, a slight amount of lubricating material will appear at the opening 21 so that the operator 10 will be apprised of the fact that the gun is full. However, lubricating material commonly used in devices of this kind, will seal the vent so that, even though pressure is continued on the supply, no further lubrication 15 will enter the gun. It will be apparent that the gun can be filled at any time, irrespective of whether it has been previously entirely emptied or not. This is a great advantage over prior devices which are filled from the 20 rear for, in devices of that kind, a pocket of air will be trapped between the new supply of grease and any grease remaining in the gun so that the grease in the gun will be shot from the discharge end thereof. Another ad- 25 vantage is, of course, that it is unnecessary to remove the cap 13 from the rear end of the gun when the gun is to be refilled and since it is only necessary to connect the discharge 30 end of the gun with the source of supply, the outer surface of the gun is not soiled by the 35 lubricating material.

In case it becomes necessary to fill the gun under circumstances where the supply cannot be placed under pressure, the gun, of course, 40 may be filled from the rear in the usual way and this process is greatly facilitated by the vent 24 which will permit escape of any air entrapped in the gun by a body of grease inserted at the rear end thereof.

Where the gun is used with a flexible hose connection, the hose may be attached to the internal threads in the discharge spout 26 and the coupling 27 will be attached to the free end of the hose. The coupling 27 will not 45 tend to separate from the nipple 31 under pressure within the coupling for the reason that the inclination of the cam groove 49 is very slight and the principal relative movement between the nipple and connector is 50 taken up by the flared portion 50 at the entrance to the cam groove. When lubrication 55 has been completed and the connector 27 is detached from the nipple 31, the valve 43 will close the nipple and the valve 36 will close 60 the connector so that further escape of the lubricating material is prevented. Any material adhering to the nipple 31 may be readily wiped away because there are no projecting pins on the nipple to catch upon the wiper. 65 The nipple, of course, may be provided with

a suitable dust cap or cover, if desired. This may be attached to the nipple by means of a peripheral groove 56 formed therein.

It will be seen from Fig. 1 that when the piston is in its rearmost position, the leather 70 14 projects beyond the flange of the cap 13. This facilitates replacement of the leather in the barrel when the cap is replaced after removal.

When the connector 27 is removed from the nipple 31, the spring 40 operates to close the valve 36 to prevent further discharge of lubricating material from the gun. The perforated washer 39 operates to assist the spring 40 in closing the valve for the reason that the washer offers a resistance to the passage of the lubricating material, thus enabling the pressure in the gun to exert a force on the washer, operating in the same direction as the spring 40 to close the valve 36. 75 80 85

It is noted that the groove 49 does not extend entirely around the nipple 31 but terminates at the periphery of the nipple at a point indicated by the reference character 57. If, for any reason, the tapered portion 30 does not fit closely into the opening in the flange 28 so as to limit the inward movement of the nipple 31, the portion 57 will bind against the face of the web 47 and hold the nipple and connector tightly together. The 90 wedging engagement at this point also holds the parts from accidental reverse rotation. 95

I claim:—

1. A grease gun comprising a barrel having a discharge spout at one end thereof, a piston arranged to reciprocate in said barrel, said barrel having a vent in the wall thereof adjacent the end of said barrel opposite said discharge spout, a ring surrounding said barrel and rotatable on said barrel, and means on said ring for opening and closing said vent when said ring is rotated to various selected positions. 100 105

2. A grease gun comprising a barrel having a discharge spout at one end thereof, a piston arranged to reciprocate in said barrel, said barrel having a vent thereon adjacent the end opposite said discharge spout, a ring rotatably mounted on said barrel in registration with said vent and having a limited portion spaced outwardly from the outer surface of said barrel to leave said vent open when said spaced portion is in registration therewith, said ring being arranged to close said vent when said spaced portion is moved out of registration therewith. 110 115 120

3. A grease gun comprising a barrel having a discharge spout at one end thereof, a piston arranged to reciprocate in said barrel, said barrel having a vent therein adjacent the end opposite said discharge spout, a supporting member mounted on said barrel, and a screw having threaded engagement with said supporting member and arranged to close said vent. 125 130

4. A grease gun comprising a barrel having a discharge spout at one end thereof, said barrel having a vent therein adjacent the end opposite said discharge spout, a ring 5 rotatably mounted on said barrel in registration with said vent and having means thereon arranged to open said vent when said ring is in one position of rotation and to close said vent when said ring is in a different position of rotation, and a stop for limiting rotation of said ring.
5. A grease gun comprising a barrel having a discharge spout at one end thereof, a ring threaded on said barrel adjacent the 15 end thereof opposite said discharge spout, a cap threaded on said barrel in the rear of said ring, said barrel having a vent therethrough in registration with said ring, said ring being arranged to close said vent when 20 in one position of rotation and to open said vent when in another position of rotation, and a stop for limiting rotation of said ring, said stop being yieldingly movable out of operative position to permit rotation of said ring beyond its normal range of movement.
6. A grease gun comprising a barrel having a discharge spout at one end thereof, a piston arranged to reciprocate in said barrel, said barrel having a vent therein adjacent the end opposite said discharge spout, a closure member mounted on said barrel, and means to tighten the engagement between the closure member and the barrel adjacent the vent in said barrel.
7. A grease gun comprising a substantially cylindrical member for receiving grease, a discharge spout at one end thereof, a ring rotatably mounted on said cylindrical member, an opening in said cylindrical member adjacent the end opposite to the spout, said ring having means thereon adapted to close said opening in one position of adjustment on said cylindrical member and being so constructed as to expose said opening when in another position of adjustment, and means for exerting pressure between said ring and the surface of said cylindrical member adjacent said opening to cause said ring member to effectively close said opening 50 while in said position of adjustment wherein said ring is adapted to close said opening.

In testimony whereof I have signed my name to this specification on this 14th day of January, A. D. 1927.
